Primary Examiner — Sandra S Snapp*Assistant Examiner* — Katherine Glennon(74) *Attorney, Agent, or Firm* — Stephen Kenny; Peter Sullivan; Foley Hoag LLP(57) **CLAIM**

The ornamental design for a watch, as shown and described.

DESCRIPTION

FIG. 1 is a perspective view of a watch showing my new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The broken lines shown in the drawings represent portions of the watch which form no part of the claimed design.
